UNITED STATES PATENT OFFICE.

SAMUEL ROSENBERG, OF MILWAUKEE, WISCONSIN, ASSIGNOR TO RELIABLE KNITTING WORKS, OF MILWAUKEE, WISCONSIN, A CORPORATION OF WISCONSIN.

DESIGN FOR A KNITTED CAP.

58,402.

Specification for Design.

Patented July 12, 1921.

Application filed August 21, 1920. Serial No. 405,205. Term of patent 7 years.

To all whom it may concern:

Be it known that I, SAMUEL ROSENBERG, a citizen of the United States, residing at Milwaukee, in the county of Milwaukee and State of Wisconsin, have invented a new, original, and ornamental Design for Knitted Caps, of which the following is a specification, reference being had to the accompanying drawing, forming part thereof.

The figure is a perspective view of a knitted cap embodying my new design.

I claim:—

The ornamental design for a knitted cap, as shown.

SAMUEL ROSENBERG.
